UNITED STATES PATENT OFFICE.

JOSEPH ALFRED WALKER, OF SPRINGFIELD, ILLINOIS

COAL-MINE DRILL.

1,271,396.

Specification of Letters Patent. Patented July 2, 1918.

Application filed April 5, 1918. Serial No. 226,892.

To all whom it may concern:

Be it known that I, JOSEPH ALFRED WALKER, a citizen of the United States, residing at Springfield, in the county of Sangamon, State of Illinois, have invented a new and useful Coal-Mine Drill; and I do hereby declare the following to be a full, clear, and exact description of the invention, such as will enable others skilled in the art 10 to which it appertains to make and use the same.

The present invention relates to a core drill which is especially adapted for mining purposes, and has for its object to provide 15 a device of this character which embodies novel features of construction whereby removable cutter bits are employed, thereby saving the loss of time and expense which is incident to filing the ordinary cutters and 20 in carrying the drills back and forth between the mine and the blacksmith shop.

Further objects of the invention are to provide a device of this character which is comparatively simple and inexpensive in its 25 construction, which can be used in connection with the standard drill operating devices now in use, which enables the cutting bits to be quickly replaced when they become dull, and which will operate quickly 30 and without loss of time, thereby reducing the time consumed in drilling and enabling the miner to get out a greater quantity of material.

With these and other objects in view, the 35 invention consists in certain novel combinations and arrangements of the parts as will more fully appear as the description proceeds, the novel features thereof being pointed out in the appended claims.

For a full understanding of the invention, 40 reference is to be had to the following description and accompanying drawing, in which:

Figure 1 is a side elevation of a core drill 45 constructed in accordance with the invention.

Fig. 2 is a longitudinal sectional view through the same.

Fig. 3 is a bottom plan view of the same 50 with the bits removed.

Figs. 4 and 5 are detail views of one of the cutting bits.

Fig. 6 is a detail view of one of the spring locking keys.

Corresponding and like parts are referred 55 to in the following description and indicated

in all the views of the drawings by the same reference characters.

Referring to the drawing, which illustrates one embodiment of the invention, the 60 numeral 1 designates an elongated tubular stock which is of the proper size for drilling a hole of the desired diameter. The interior of the tubular stock is hollow and formed with smooth sides so as to receive 65 the core of coal or rock which is produced by the operation of the drill, while the exterior of the stock is surrounded by a spiral flange 2 which serves to move the cuttings from the bits to the outer end of the hole. 70 One end of the tubular stock 1 has a socket 3 applied thereto, said socket being shown for the purpose of illustration as threaded to the stock at 4, and as formed with a tapering polygonal opening 5 adapted to be engaged by any standard drill operating mechanism. The opposite end of the stock 1 is exteriorly threaded at 6 to receive an annular cutting head 7, the exterior of the cutting head being provided with a series of 80 inclined ribs 8 which project outwardly slightly beyond the edge of the spiral flange 2, the extreme external diameter of the cutting head 7 and ribs being thus slightly greater than the extreme external diameter 85 of the tubular stock 1 and spiral flange. One end of the cutting head 7 is rabbeted and threaded to receive the threaded end 6 of the stock 1, the interior diameter of the cutting head being otherwise the same as that of the 90 tubular stock.

The free end of the annular cutting head 7 is formed with a series of transverse slots 9, said slots extending inwardly at an inclination or angle to the longitudinal axis 95 of the stock, and opening through both the inner and outer sides of the cutting head. One of these slots 9 is provided for each of the ribs 8, the inclination of the slots corresponding to the inclination of the ribs and 100 being the proper inclination for the removable cutting bits 10. One side of each of the slots 9 is formed with a longitudinally extending depression 11 which is substantially V-shaped in cross section. The cutting bits 10 have a cross section corresponding to that of the slots 9 and depressions 11 and are insertable within the slots from the end of the cutting head. The provision of the slots 9 enables the cutting bits to have a width 110 equal to the thickness of the walls of the cutting head, and also enables the bits to be

readily pried out of position by inserting a tool under the bits in the ends of the slots.

The bits 10 are preferably provided with a cutting edge 10^a at each end thereof, therefore by making them reversible, so that when one of the cutting edges becomes dull it is merely necessary to reverse the position of the bit in order to bring a fresh cutting edge into working position. Under some conditions it may be found desirable to use a spring locking key 12 for positively holding the bits in position within the cutting head. These locking keys 12 are insertible in transverse grooves 13 formed in the cutting head at the sides of the slots 9, and are provided at their middle portions with crimps 12^a adapted to spring into depressed seats formed in the cutting bits 10. The locking keys can thus be forcibly inserted in position or removed therefrom by means of a suitable punch, and when they are in position they lock the cutting bits securely in place and prevent any possibility of the bits becoming accidentally displaced. The depressed seats 14 are placed at the middle of the cutting bits so that the use of the locking key does not interfere with the reversibility of the bits.

In the use of the drill the bits 10 are inserted in operative position within the inclined slots 9 of the cutting head 7, whereupon the drill is ready for use and can be operated by any conventional or standard drill operating device. When using the device in connection with soft coal it can be operated by hand. The cutting bits 10 operate in the usual manner to produce an annular opening in the coal or rock, leaving a core which enters the tubular stock 1. The coal has escape from the bits through the spaces between the ribs 8 of the cutting heads 7, and then carried outwardly to the end of the hole by the spiral flange 2 of the stock 1. When the bits become dull they can be readily reversed or replaced with fresh bits, and the necessity of stopping to file the cutters is thus avoided. It is also unnecessary to carry the drills back and forth between the mine and the blacksmith shop for the purpose of having the drills sharpened, and with this device a coal miner can do the necessary drilling in a very short period of time, thereby giving him more time to load coal and enabling him to very materially increase his output.

Having thus described the invention, what I claim as new and desire to secure by Letters Patent, is:

1. A core drill including an elongated tubular stock, an annular drilling head applied to one end of the stock and provided at its free end with a series of inwardly extending slots which are inclined to the axis of the stock, one side of each of the slots being formed with a longitudinal depression, and cutting bits fitted removably in the slots and depressed sides thereof, said cutting bits projecting beyond the cutting head and being inclined to the axis of the stock.

2. A core drill including an elongated tubular stock, an annular drilling head applied to one end of the stock and provided upon its exterior with a series of inclined ribs, the end of the cutting head being provided with a series of slots which extend inwardly at an inclination to the axis of the stock and each have one side provided with a longitudinal depression, one of the slots being provided for each of the ribs and the slots extending transversely of the cutter head and opening through both the inner and outer walls thereof, and cutting bits fitted removably within the said slots and projecting beyond the cutting head.

3. A core drill including an elongated tubular stock provided upon the exterior thereof with a spiral flange, an annular cutting head fitted upon one end of the tubular stock and provided upon the exterior thereof with inclined ribs which project outwardly slightly beyond the spiral flange of the stock, the end of the cutting head being provided with slots which extend inwardly at an angle to the axis of the stock and each have one side provided with a longitudinal groove, one of the slots being provided for each of the exterior ribs of the cutting head and the slots opening through both the outer and inner walls of the cutting head, and bits fitted removably within the slots and projecting beyond the cutting head, said bits having a width corresponding to the thickness of the cutting head.

4. A core drill including an elongated tubular stock, an annular drilling head applied to one end of the stock and provided at the end thereof with a series of slots which extend inwardly, one side of each of the slots being provided with a transverse grooved seat, cutting bits fitted removably within the slots and provided with depressed seats adapted to register with the grooved seats of the slots when the bits are in position, and spring locking keys insertible in the grooved seats and formed with crimped portions adapted to spring into the depressed seats of the cutting bits.

5. A core drill including an elongated tubular stock, an annular drilling head applied to one end of the tubular stock and provided upon the exterior thereof with a series of inclined ribs, the end of the cutting head being provided with a series of slots which extend inwardly at an angle to the axis of the stock and each have a longitudinal depression on one side thereof and a transverse groove at the opposite side, one of the slots being provided for each of the ribs and the slots opening through both the interior and exterior walls of

the cutting head, cutting bits fitted removably within the slots and projecting beyond the head, said bits being provided with depressed seats which register with the before mentioned transverse grooves when the

bits are in position, and spring locking keys insertible within the transverse grooves and formed with crimped portions adapted to spring into the depressed seats of the bits.

10 6. A core drill including an elongated tubular stock, an annular drilling head applied to one end of the stock and provided upon the exterior thereof with a series of inclined ribs, the end of the head being provided with a series of slots which extend inwardly at an inclination to the axis of the stock and each have one side provided with a longitudinal depression while the other side is provided with a transverse groove,

one of the slots being provided for each of 20 the exterior ribs of the head and the slots opening through both the interior and exterior walls of the head, reversible cutting bits inserted removably in the slots and each provided at its middle portion with a depressed seat adapted to register with the before mentioned transverse groove when the bit is in position, and spring locking keys insertible in the transverse groove and formed with crimped portions adapted to 25 30 spring into the depressed seats of the bits.

In testimony whereof I have signed my name to this specification in the presence of two subscribing witnesses.

JOSEPH ALFRED WALKER.
